PADDLE FOR PATTING THE SKIN TO STIMULATE CIRCULATION

Shirley B. Langham, 23 Rock Crest Drive, Dallas, Tex.

Filed Oct. 21, 1960, Ser. No. 62,571

Term of patent 14 years

(Cl. D83—1)

FIG. I

FIG. II

FIG. III

FIG. IV

FIG. V

FIG. I is a top plan view of the paddle for patting the skin to stimulate circulation, showing my new design;

FIG. II is a side elevational view thereof;

FIG. III is a front end view thereof;

FIG. IV is a rear end view thereof;

FIG. V is a bottom plan view thereof.

I claim:

The ornamental design for a paddle for patting the skin to stimulate circulation, substantially as shown.
